UNITED STATES PATENT OFFICE.

RICHARD L. LLOYD, OF PORTSMOUTH, AND ROBERT D. SIMPSON, OF COLUMBUS, OHIO,
ASSIGNORS, BY MESNE ASSIGNMENTS, TO UNITED SHOE MACHINERY COMPANY,
OF PATERSON, NEW JERSEY, A CORPORATION OF NEW JERSEY.

MACHINE FOR MARKING BUTTONHOLE-FLIES.

1,198,462.

Specification of Letters Patent. Patented Sept. 19, 1916.

Application filed March 15, 1912. Serial No. 684,074.

To all whom it may concern:

Be it known that we, RICHARD L. LLOYD and ROBERT D. SIMPSON, citizens of the United States, residing, respectively, at 5 Portsmouth and Columbus, in the counties, respectively, of Scioto and Franklin, State of Ohio, have invented certain new and useful Improvements in Machines for Marking Buttonhole-Flies, of which the following 10 is a specification.

This invention relates to the marking of shoe uppers to indicate the position on the upper where certain operations are to take place, such as the making of buttonholes, 15 attachment of buttons, etc.

It has been the practice to mark the locations of buttons and buttonholes on the shoe upper material by piercing or indenting the material of the upper with a marking tool 20 or a series of marking devices forming part of a marking machine. In certain upper materials, such as soft leather, cloth, canvas, etc., the puncture or indentation subsequently closes up or disappears so that when 25 the time arrives to utilize the indication mark it is not discernible. It has also been the practice to mark upper materials with inked markers but the ink has a tendency to spread particularly in cloth and canvas, and 30 the exact location of the mark is not easily ascertained. Furthermore the appearance of the upper is injured by the spreading ink or colored dye. When chalk is used the mark becomes smeared and the indication 35 is so blurred as to be useless.

A conspicuous feature of our invention consists in a machine for marking shoe upper materials provided with marking means arranged to place a dry indelible indication 40 upon the upper material which will always be discernible by contrast with the adjacent unmarked portions of the material. Incidentally the machine involves the application of a novel method of marking uppers. 45 We accomplish the result stated by employing heated markers to cauterize the surface

of the material. Preferably these markers are electrically heated.

Another feature of the invention consists in a structure providing two series of cauterizing markers with means for causing a heating electric circuit to pass through either series. Such a construction permits the marking of either face of the material.

A further feature resides in a novel construction of electrically heated markers.

Another feature of the invention consists in two series of aligned cauterizing marker elements with means for simultaneously moving both series of elements to vary their 60 relative spacing, and with means for heating either series of marker elements.

A still further feature of the invention consists in the means for adjusting a series of markers longitudinally of a guiding element so as to determinately vary the spacing between the markers.

These and other features and advantages will be more fully apparent from a reading 70 of the following specification in connection with the accompanying drawings, in which—

Figure 1 is a front elevation of a marking machine constructed in accordance with a preferable embodiment of the invention; Fig. 2 is a transverse vertical section of the 75 machine shown in Fig. 1; Fig. 3 is a top plan view of the machine shown in Figs. 1 and 2, the cover being removed to disclose the interior arrangement; Figs. 4 and 5 are views in top plan and front elevation of the 80 knee operated lever element for controlling the spacing of the marking elements; Fig. 6 is a plan view of the yoke by means of which the lower series of marking elements are moved to effect marking of the work; 85 Figs. 7 and 8 are views in side and front elevation respectively of one of the movable blocks carrying the upper and lower marking members, the block shown in the present instance being one of the terminal blocks of 90 the series; Fig. 9 is a view in front elevation of the other terminal block of the series,

including the switch for directing the heating current to the upper or lower series of markers; and Fig. 10 is a top plan view of the parts shown in Fig. 9; and Figs. 11 and 5 12 are views in top plan and side elevation respectively of one of the links connecting the marker carrying blocks with the spacing lever; Fig. 13 is a diagrammatic view illustrating the current distribution and control; and Fig. 14 is a detail, in section, of the end gage used to position the end of the work relatively to the markers.

The machine comprises a suitable support including a tubular standard 1 whose upper 15 end is secured to and supports a base 2, upon which is mounted a rear wall 3 and side walls 4 forming a housing for the operating parts of the machine. A hinged cover is preferably provided for the housing. At 20 the front edge of the base a work supporting board or plate 5 is secured and is formed to provide its inner edge with a curve corresponding substantially with the curve of the buttonhole fly of a shoe upper. From 25 the curved edge of the work support rearwardly, the base 2 is slotted, as shown at 6, the rear edge of the slot having an upstanding flange or guide plate 7. This guide plate is intended to receive and guide a series of 30 marker carrying blocks or marker units for movement longitudinally of the guide to vary their spacing. These units or blocks, indicated at 8, have their lower rear faces inwardly offset and provided with vertical 35 bifurcating slots 9 therein extending upwardly from the base of the block. These slots are of sufficient width to receive the guide flange or plate 7 therein, so that the blocks are supported on the guide plate by 40 means of these slots. The front face of each of the blocks, at a point between its upper and lower end, is recessed inwardly, as at 9^a to provide space for the insertion of the edge of the fly so that the work may be positioned between spaced upper and lower 45 marking elements mounted on the block above and below this bifurcation. The outer face of each of the blocks above and below the recess 9^a is provided with insulating strips or plates 10 and 12. The upper plate 10 carries an insulated stud 11 and the lower plate an insulated stud 15 to which the marker elements are secured, as later explained. The lower insulating plate 12 is 55 provided with a longitudinal slot 14 therein extending vertically of the block and pins 13 secured to the block 8 extend through this slot and guide the lower plate 12 for vertical movement toward the upper plate 10 which is rigidly secured by suitable means 60 to the outer face of the block. The bases of the lower insulating plates 12 carry resilient hook elements 16 adapted to clasp the edge

of a frame 17 positioned below the bed 2 and pivoted at its rear end at 19 to the bed 65 of the machine. The engaged edge of the bar 17 of this frame is formed on a curve corresponding to the curve of the slot 6 and curved edge of the work support 5. It is arranged to be moved upwardly to move the 70 lower insulated blocks 12 upwardly, by means of a pivoted link 20 attached at its lower end to a bar 18 of the frame and pivoted at its upper end to a lever 21. This lever is fulcrumed at 22 upon the base of 75 the machine and has at its forward end a pivoted rod 21^a extending downwardly through the tubular standard 1 with its lower end in turn pivoted to a treadle 21^b having a lateral offset, (Fig. 1) arranged to 80 be engaged by the foot of the operator. Movement of the treadle downwardly serves to pull the frame 17 upwardly through link 20 so that the series of lower insulated plates 12 are moved upwardly toward the 85 upper series. At the same time, the rear end of lever 21 is arranged to close an electric switch in a circuit which includes electrically heated markers carried by the upper and lower series of insulated blocks 10 and 90 12. To this end, a projecting bar switch 23 is carried by the rear end of lever 21 with suitable intermediary insulation and is arranged to engage and bridge spaced switch contacts 24 when so moved. When a second 95 break in the circuit has been closed through a manually operated selective switch, the current will pass through either the upper or lower set of marker elements carried by the insulated series 10 and 12. The marker 100 elements are formed by a single length of flexible conducting ribbon 25, which extends along the upper series of plates 10 and is provided with V-shaped portions, the lower ends of which engage the insulated studs 105 11, this ribbon at one end of the series of upper plates 12 being then bent downwardly and extended along the line of lower plates 12 in a similar manner with inverted V-shaped portions or loops embracing the insulated studs 15 of the lower series of plates. The extremities of these loops or V-shaped 110 portions are in the form of sharp bends 26 which project above the edges of the inward recesses 9^a of the blocks. The terminals 115 of the conducting ribbon 25 opposite the closed end of the ribbon or at the left end of the series shown in Fig. 3 are connected with switch jaws 27, 28. Adjacent these switch jaws is located a manually controlled selective switch in the form of a pivoted switch blade 29 having an operating handle 30 and arranged in line with switch jaws 27, 28. By connecting the blade 29 with one of the jaws 27 or 28, the current 120 125 may be caused to pass through either the

upper or lower series of marking bends 26 of the ribbon 25. The ribbon itself being flexible, provides a series of longitudinally extensible and contractible cauterizing portions as well as two series of opposed cauterizing portions relatively movable. The electric circuit for effecting this heating is best seen in Fig. 13 in which a wire 35 leading from one side of a source of current is connected to one of the spaced contacts 24 of the bridge switch. The other contact of the switch is connected with a resistance coil 37, the opposite end of this coil being in turn connected to a rheostat 38, the current passing through the rheostat and out by a wire 31 to the knife switch 29, thence through either the upper or lower series of marking bends 26 of the ribbon 25, depending upon the connection of the switch blade 29, to the other side of the source of current. A wire 34 is connected to the closed end of the ribbon 25 and leads from said ribbon to the other side of the current source.

It will be understood that in marking the buttonhole fly, it is placed upon the work support 5 with the edge of the fly extending into the recess 9^a of the blocks 8 and positioned by eye so that the edge of the fly is spaced from the markers substantially uniformly and for the desired distance. The end of the fly is positioned at the appropriate distance from the first marking element of the series by means of an end gage in the form of a swinging arm 39, whose end forms a stop against which the end of the fly rests. This end gage may be swung to vary the distance of the first mark from the end of the fly by means of a thumb bolt 39^a. The number of buttonholes to be marked as well as the relative spacing between the buttonholes will vary in different shoes and consequently, before the treadle 21^b is operated to close the circuit and lift the lower series of markers, the markers themselves should be properly adjusted. These markers will bear certain indications, such as numbers, by means of which the operator can readily utilize the desired number of marking elements. To space properly the selected number of elements, the following mechanism is employed: Each of the series of blocks 8 except the first one has its rear formed with a perforation or socket 42. At the rear and right end of the base, as viewed in Fig. 3, a spacing lever 43 is fulcrumed on a vertically extending shaft 47. This lever 43 is provided with a plurality of longitudinally extending and alined journaling apertures therein and a series of links in the form of rods 40 are arranged to connect this adjusting lever with the successive blocks 8. To this end the rods 40 are each bent to a

particular form and at their forward ends are provided with depending portions 41 seated in the sockets 42 of the blocks 8. At their rear ends these rods carry threaded sleeves 44 having extensions 45 with depending pins 46 designed to journal in the successive apertures in the adjusting lever 43. The threaded sleeve 44 provides for adjustment of the length of the rods. The links 40 and the lever 43 are figured to provide a definite and ascertained movement of the links 40 and of the blocks 8, connected to their outer ends, so that when the adjusting lever is moved the links 40 will slide the blocks longitudinally on the guide plates 7 and will space the blocks equally at various points of movement of the adjusting lever 43. The spacing of the marking blocks occurs from one end of the series and relative to an end block of the series which is fixed. In Fig. 3 of the drawings this end block is found at the extreme left hand end of the series and is secured in desired position on the guide plate 7 by means of a set screw 48. It is, of course, understood that there is no link 40 connected to this fixed marking member. Movement of the lever 43, will, therefore, move the successive blocks from and toward each other and from and toward the fixed end block to give the desired spacing of the markers carried by the blocks. The adjusting movement of the lever is preferably limited by stop pins 49 and 50 (Fig. 3). Adjusting movement of the lever is effected by the operator through a rod 51 co-axial with and depending from the shaft 47 which forms the axis about which the lever turns. This rod 51 has detachably secured to it the rear end of a bar 52. As seen in Fig. 4, the rear end of this bar is formed as a split socket or collar 53 with an operating handle 54 arranged to clamp the collar about the rod 51. The forward end of the bar 52 is provided with an elongated slot 55 therein with a cross bar 56, which is dovetailed into the slotted portion of the bar 52 and has a wing nut 57 for clamping the cross bar at various distances from the forward end of the bar 52. This adjustment enables the cross bar to be positioned according to the location of the knee of the operator which is to be inserted between the spaced rods 58 and 59 depending from the cross bar 56 and adjustable on the cross bar by means of nuts 60 and 61. Movement of the operator's knee will swing the bar 52, turning the rod 51 and shaft 47 to swing the adjusting lever 43.

With the fly inserted between the properly spaced markers, the operator depresses the treadle 21^b, moving upwardly the lower set of insulated blocks 12 with their mark-

ing points to engage the fly between the two series of marking points, the ribbon 25 being sufficiently flexible to permit this movement. When the knife switch 29 has 5 been moved to close the circuit through the lower series of marking points, the under face of the fly will be cauterized to provide a series of dry indelible marks indicating the locations of the buttonholes. If the up- 10 per series of marking points has been energized, these points will similarly mark the upper face of the fly. The indication mark made by the cauterizing of the surface of the upper material is not only dry and 15 indelible, but will always be clearly discernable, whatever the nature of the materials, because of the effect of the cauterization upon the material itself. The cauterization will always change the color of the cauterized spot either to a different shade so that 20 the mark will be discernible under all conditions.

The novel method herein disclosed, which is characterized by the step of cauterizing 25 the surface of the material to form indicating marks, is not claimed herein but forms the subject-matter of our divisional application filed February 8, 1916, Ser. No. 76,940.

Owing to the described construction of 30 the marker elements and their adjusting devices, it will be obvious that these parts may be readily detached from the machine for repair or adjustment and without disturbing 35 the operative connections of any of the other parts of the machine.

The described construction is specifically arranged and adapted for marking button-hole flies, but it is to be understood that the 40 invention is not limited to a machine arranged for this specific purpose only, but that the parts may be varied to accommodate the machine for marking for buttons, eyelets, etc., within the scope of the invention, as expressed in the following claims.

Having thus described our invention, what we claim as new and desire to secure by Letters Patent of the United States is:—

1. A machine of the class described, comprising a guide of predetermined shape, a plurality of elements engaging said guide and movable longitudinally of the guide, means for adjusting said elements longitudinally of the guide to vary their spacing 50 with respect to each other, marking members mounted on said elements and arranged to be electrically heated to cauterizing temperature, and means for moving said marking members simultaneously, to bring said 55 marking members into engagement with the material to be marked, with means for closing an electric circuit to heat said marking members.

2. A machine of the class described, comprising guiding means, a plurality of marking elements coöperating with said guiding means, each element comprising opposed co-operating markers and said plurality of elements providing opposed series of markers arranged to be electrically heated to cauterizing 65 temperature, and means for electrically heating one of said series of markers. 70

3. A machine of the class described, comprising a guide element of predetermined shape, a series of spaced electric marking 75 devices normally engaging said guide element, means for electrically heating said devices to cauterize the material when brought into contact therewith, and means for simultaneously moving said devices to 80 the desired position on said guide element and in determinately spaced relation with each other.

4. A machine of the class described, comprising a series of marker elements and a continuous ribbon connecting all of said elements and bent to form a plurality of cauterizing points, and means for heating said points by passing a current of electricity 85 through said ribbon. 90

5. A machine of the class described, comprising a series of upper cauterizing elements, a series of lower cauterizing elements, means for heating either series of elements by passing a current of electricity there- 95 through and means for moving one of said series of elements toward the other and into contact with material positioned between the upper and lower series of elements. 100

6. A machine of the class described, having a series of longitudinally movable insulating members, and a flexible ribbon-like electrical conductor formed with spaced bends secured to said insulating members 105 and providing marking points arranged to cauterize when electrically heated.

7. A machine of the class described having, in combination, a series of spaced insulating heads, means for moving said heads 110 toward and from each other to vary their relative spacing, lengths of electrical conductors secured to each head and forming a cauterizing marker, and means to heat electrically said lengths of conductors to 115 cauterizing temperature.

8. A machine of the class described having, in combination, an upper series of insulated heads, a lower series of alined insulated heads, with means for simultaneously 120 moving the upper and lower alined insulated heads toward and from each other to vary their relative spacing, lengths of electrical conductors secured to each head and forming a cauterizing marker, means for 125 electrically heating said conductors to cauter-

izing temperature and means for effecting relative movement between the upper and lower series of heads to mark material placed between said series.

- 5 9. A machine of the class described having a flexible ribbon of electrically conductive material provided with a plurality of spaced marking portions, with means for electrically heating said marking portions, and means 10 for longitudinally distending and contracting said ribbon to vary the spacing of its marking portions.

- 10 10. A machine of the class described having a plurality of spaced buttonhole location 15 marking members, means for heating said members to cauterizing temperature, and means to vary the spacing of said members.

- 10 11. A machine of the class described having a plurality of spaced buttonhole location 20 marking members connected for simultaneous movement toward and from each other to vary their relative spacing, means for guiding said members during spacing movement, and means for heating said members to cauterizing temperature.

- 25 12. A machine of the class described having a plurality of spaced buttonhole location markers, with means for simultaneously moving said markers toward and from each 30 other to vary their relative spacing, means to electrically heat said markers to cauterizing temperature, a work support, and means for effecting movement of said markers in the direction of work.

- 30 13. A machine for marking shoe uppers having a plurality of spaced markers arranged to be electrically heated to cauterizing temperature, guiding means coöperating with said markers to provide a desired linear 40 arrangement thereof, with means for varying the relative spacing of said markers.

- 40 14. A machine for marking buttonhole locations on shoe uppers comprising a plurality of spaced marking elements, each carrying 45 a buttonhole location marker of electrical resistance material arranged to be electrically heated to cauterizing temperature, guiding means coöperating with said marking elements to provide a desired curvilinear 50 arrangement of their markers, means for moving said marking elements to vary the relative spacing of their markers, a work support, and means for effecting relative movement between said work support and 55 said plurality of marking elements.

- 55 15. A machine for marking shoe uppers having a plurality of spaced marking elements, each constructed to provide opposed coöperating markers arranged to be electrically heated to cauterizing temperature, guiding means coöperating with said marking elements to provide a desired linear arrangement of their markers, means for mov-

ing said marking elements to vary the relative spacing of their markers, and means for effecting relative movement between the plurality of opposed markers in a direction to mark material interposed therebetween.

16. A machine for marking shoe uppers having a plurality of spaced marking elements constructed to provide pairs of opposed relatively movable markers, each marker being formed of electrically resist- 70 ant material shaped to provide a work contacting surface of desired configuration and 75 arranged to be heated to cauterizing temperature by an electric current, with means to move relatively the plurality of opposed markers.

17. A machine for marking buttonhole lo- 80 cations on shoe uppers having a plurality of spaced marking elements constructed to provide pairs of opposed and relatively movable coöperating markers arranged to be electrically heated to cauterizing tempera- 85 ture and including a marker formed of a length of electrically resistive material having a bend therein forming a buttonhole location marking surface.

18. A machine for marking shoe material 90 having a plurality of spaced marking elements each constructed to provide a pair of opposed coöperating markers arranged to be electrically heated to cauterizing tempera- 95 ture, said plurality of elements providing series of coöperating opposed markers, work supporting means between said opposed series, and means for effecting relative movement between said series in the direction of the work supporting means.

100 19. A machine for marking shoe uppers having a plurality of pairs of opposed coöperating markers arranged for relative movement, each marker comprising a bent portion of electrically resistive material ar- 105 ranged to be heated to cauterizing tempera- ture by an electric current, guiding means coöperating with said plurality of pairs of markers to provide a desired linear arrange- 110 ment thereof, means for varying the relative spacing of the pair of markers, and means to effect simultaneous relative movement of the opposed markers.

115 20. A machine for marking buttonhole lo- cations on shoe uppers comprising a plural- 120 ity of spaced marking elements each constructed to provide opposed coöperating markers arranged for relative movement and formed of electrically resistive material ar- 125 ranged to be heated to cauterizing tempera- ture by an electric current, guiding means coöperating with said marking elements to provide a desired curvilinear arrangement of their markers, means for moving said elements toward and from each other to vary the relative spacing of their markers,

and means for effecting simultaneous relative movement of the opposed markers of the plurality of elements.

21. A machine for marking shoe material having a plurality of spaced relatively movable arms with markers of electrically resistant material supported by said arms and electrically connected in series and arranged to be heated to cauterizing temperature by the passage of an electric current therethrough and means for effecting relative movement of the arms and markers to vary their relative spacing.
- 10 22. A machine for marking shoe uppers having a plurality of spaced marking ele-

ments each constructed to provide opposed relatively movable and coöperating markers of electrically resistant material adapted to be heated to cauterizing temperature by the passage of an electric current therethrough, 20 each of said elements also providing supporting means for work inserted between the opposed markers.

In testimony whereof we affix our signatures in presence of two witnesses.
